UNITED STATES PATENT OFFICE.

TORQUATO TASSO FISCHER, OF NEW YORK, N. Y.

DESIGN FOR A PIANO PEDAL MEMBER.

SPECIFICATION forming part of Design No. 30,998, dated June 13, 1899.

Application filed May 20, 1899. Serial No. 717,650. Term of patent 7 years.

To all whom it may concern:

Be it known that I, TORQUATO TASSO FISCHER, a citizen of the United States, residing at New York city, county of New York, State of New York, have invented and produced a certain new, original, and useful Design for a Piano Pedal Member, of which the following is a full, clear, and exact description.

My invention relates to a new and original design for a piano pedal member.

In the illustration shown in the accompanying drawings, Figure 1 shows a side elevation of my design. Fig. 2 is a plan view.

My design consists, primarily, of a horizontal base A, having an upright extension A'. The sides of the upper end of this extension

A' are inclined inwardly toward a point. B' are wings projecting in opposite directions from the upper end of the extension A'.

The leading feature of my design is the upright extension A', having its sides tapered toward the upper end thereof and the two laterally-projecting wings at the top of said upright extension.

What I claim is—

The design for a piano pedal member substantially as herein shown and described.

TORQUATO TASSO FISCHER.
